UNITED STATES PATENT OFFICE.

MICHAEL SAUTTER, OF SPOKANE, WASHINGTON.

HUSKING MITTEN.

1,423,543.

Specification of Letters Patent. Patented July 25, 1922.

Application filed October 14, 1920. Serial No. 416,817.

To all whom it may concern:

Be it known that I, MICHAEL SAUTTER, a citizen of the United States, residing at Spokane, in the county of Spokane and State 5 of Washington, have invented certain new and useful Improvements in Husking Mittens, of which the following is a specification.

The object of this invention is to provide 10 a light, inexpensive and comfortable mitten by the use of which an ear of corn from which the husk is to be removed may be securely held. The invention seeks to provide a mitten for the stated purpose which may 15 be readily secured in position upon the hand and which will be flexible so as to conform to the movement of the hand in operation and at the same time be durable, and the invention seeks also to provide a device which 20 will protect the wrist of the user and which will not permit the fastening devices to assume a position in which it will be difficult to bring them into proper relation to secure the mitten in place. The invention is illus- 25 trated in the accompanying drawing and consists in certain novel features which will be particularly pointed out in the appended claims.

In the drawings—

30 Figure 1 is a perspective view of my improved mitten viewed from the back thereof;

Fig. 2 is a similar view showing the palm of the mitten;

Fig. 3 is a longitudinal section.

35 In carrying out my invention, I employ a lining or backing ply 1 which, as shown clearly in Fig. 3, is formed in two members or blanks, one of which constitutes the back of the mitten and the other forms a palm portion. This lining or backing member is 40 also constructed with tongues or extensions, indicated at 2, which constitute, when brought into proper relation, a pocket for the thumb. Over the palm portion of the 45 backing or lining member 1, I place a facing 3 of leather which extends over the entire palm portion of the mitten and has an extension or tongue 4 which covers the inner side of the thumb pocket or stall. Upon 50 the outer side of the backing ply, I place along the edge thereof a reinforcing or binding strip 4^a of leather and through the said reinforcing or binding strip, both sections or members of the lining, and the edge of the 55 palm facing 3 I insert tubular rivets 5, the

open ends of said rivets being split and upset against the palm face of the mitten so that all the parts will be firmly secured together without sewing which is liable to rip, as will be readily understood. At the extreme tip 60 of the mitten, I employ larger rivets, indicated at 6, which when upset will present projections beyond the surface of the mitten adapted to engage the husks of the corn and thereby aid in obtaining a firm grip upon the 65 same. Other rivets, indicated at 7, are inserted through the facing 3 whereby the lining will be held smoothly to the facing throughout its area and a roughened surface will be provided over the entire face of the 70 palm portion of the mitten and the inner side of the thumb. Near the outer end of the mitten, I provide hooks 8 which are disposed in a line across the mitten, as clearly shown in Fig. 2, and have their prongs or 75 beaks directed toward the inner end or wrist of the mitten so that they will engage in the corn husk and firmly hold the same and at the tip of the thumb I secure upon the inner side thereof a hook 9 of the same form as 80 the hooks 8 so that when the mitten is in use a firm grip upon the corn will be obtained.

Around the inner or lower end of the mitten over the lining or backing member 1 and 85 over the outer side of the facing 3 I secure a wrist band 10 of leather, the said wrist band being secured to the mitten by rivets 11 and presenting a free end portion 12, as shown in Fig. 1, at the back of the wrist 90 and upon the outer side of which I secure buckles 13. Slots 14 are provided adjacent the buckles and upon the wrist band on the palm side of the same and below the base of the thumb stall or pocket 2, I secure the 95 ends of fastening straps 15 which straps are inserted through the slots 14 from beneath the wrist band and through the buckles 13 so as to be engaged by the buckles and secure the wrist band firmly around the wrist 100 of the wearer so that the mitten will be held in position. The free ends of the straps 15 are equipped with buttons, plates or other form of stops 16 which are of such dimensions that they will not pass 105 readily through the buckles 13 so that while the straps may be loose enough to permit the removal of the mitten or the placing of the same upon the hand, the straps cannot be entirely released from the 110

buckles and, consequently, the mitten may be very quickly secured on or removed from the hand.

The lining, backing, or foundation 1 of the mitten will preferably be of some textile fabric such as heavy cotton, canvas or wool so that it will be soft and comfortable to the hand and will be light enough to permit free movement of the hand and fingers in grasping an ear of corn. The leather facing and the leather wrist band will reinforce the portions of the mitten which are subjected to rough usage and will enable the same to withstand wear so that the device will prove very durable and the wrist band will thoroughly protect the wrist of the user so that it will not be easily strained or otherwise injured in the husking operation. The several parts are secured together by rivets so that they will not be easily separated and frequent repairs will not be needed in contradistinction to a mitten in which the parts are secured by sewing or some similar means. It will be noted that the surface of the palm portion of the mitten is studded with rivet heads and these rivets may be employed in such number as may be deemed desirable in order to provide a very efficient gripping surface without adding undue weight to the device. The greater rivets 6 and the hooks 8 provide means

whereby the husks may be efficiently held at the point where the greatest gripping action is naturally applied and also serve to reinforce and protect the working surface of the mitten at the points where the greatest wear naturally occurs. The mitten is obviously simple and cheap and will be found highly efficient when in use.

Having thus described the invention, what is claimed as new is:

1. A husking mitten comprising a textile base, a reinforcing strip disposed upon the back of said base along the edges thereof, a facing member covering the palm portion of said base, the edges of the base being disposed between the reinforcing strip and the facing, headed fastening devices inserted through the said base and the palm facing, and other headed fastening devices inserted through the reinforcing strip.

2. A mitten comprising a textile base, composed of a palm member and a back member, a wear-resisting facing covering the entire outer face of the palm member, a reinforcing strip disposed upon the back member along the edge thereof, and fastenings inserted through said strip, the palm and back members of the base, and the facing and upset against the facing.

In testimony whereof I affix my signature.

MICHAEL SAUTTER. [L.S.]
